UNITED STATES PATENT OFFICE.

MYRON H. CLARK, OF HASTINGS-UPON-HUDSON, NEW YORK, ASSIGNOR TO GOODYEAR'S METALLIC RUBBER SHOE COMPANY, A CORPORATION OF CONNECTICUT.

BOOT OR SHOE.

1,162,454.

Specification of Letters Patent. Patented Nov. 30, 1915.

Application filed March 6, 1915. Serial No. 12,477.

To all whom it may concern:

Be it known that I, MYRON H. CLARK, a citizen of the United States, and a resident of Hastings-upon-Hudson, county of Westchester, and State of New York, have invented certain new and useful Improvements in Boots or Shoes, of which the following is a full, clear, and exact description.

This invention relates to articles of rubber 10 footwear and the method of producing same, and has for an object to produce in such articles a smooth even interior surface.

I accomplish my object by providing the boot or shoe with an inner stratum or lining 15 of vulcanized rubber or rubber compound all hereinafter more fully set forth, and illustrated in the accompanying drawings wherein;

Figure 1 is a longitudinal sectional view 20 of a partly built boot on its last; Fig. 2 is a similar view of a completed boot; Fig. 3 is a similar view corresponding to that in Fig. 1 showing a modified construction; and Fig. 4 is a longitudinal section of the same 25 in its next stage of manufacture.

To build a boot embodying my improved construction, I have found the most effective method, and that which I wish to protect, to be the following:

30 I apply to a last 5, Fig. 3, a ply of fabric 6, covering the leg and foot portion but merely overlapping the sole portion. To the sole portion, and covering the overlapping edges of the fabric 6 I apply an insole 7.

35 A sheet of rubber 8 is then superposed on the above named parts so as to completely cover them, and the thus far built up structure set and unified by the vulcanizing process. Thus far the fabric ply 6 and the in-

40 sole 7 have formed the inner surface next to the last 5. I therefore next strip the united material therefrom, and in so doing reverse the relation of the plies so that the rubber stratum, which was, up to this point, located 45 on the outside, becomes the inside layer. I then replace the whole, while reversed, on the last, and finish by any preferred method of building boots, the additional part being shown in Fig. 2 at 9. The procedure above

50 described is that illustrated in Figs. 3 and 4, wherein the margin of the fabric ply 6 is applied to the last before the insole 7. I

prefer this method in that it provides in the finished article a more even surface for the foot than that I have shown in Fig. 1 55 in which I apply the insole 7 before the fabric 6. Under some circumstances, however, I contemplate using the latter procedure and desire to protect it.

The turning of the inside plies above described and subsequent replacing of them on the last gives the fabric a uniform stretch throughout, thereby removing any wrinkles therein, while the inside of the completed boot consists of a slightly compressed, but 60 smooth structure of vulcanized rubber, this stratum eliminating the tendency to wear out socks, so objectionable in boots of the conventional construction.

In the conventional boot, embodying as it 70 does a ply of fabric on one side of which are superposed successive plies of plastic material, a flexion of the boot is accompanied by an unbalanced compression or stretch of the material, the fabric, which is substantially non-elastic, determining the line of flexion. On the other hand, a boot such as is produced by the method I have hereinbefore described, is found to be extremely 75 flexible. This flexibility is attributable to the 80 fact that the non-elastic element, the fabric, is midway between two plies of elastic material, and any flexing is accompanied by a balanced compression and stretch of the latter elements.

Having described my invention, what I claim and desire to have protected by Letters Patent is:

The method of manufacturing footwear, which consists in applying to a last a ply 90 of fabric, and an insole and then a layer of vulcanizable plastic; submitting said parts to the vulcanizing process; removing said parts from the last; turning same inside out; replacing said parts on the last in 95 their reversed relation; and finishing by any preferred method.

Signed at New York city, in the county of New York, and State of New York, this 3rd day of March, 1915.

MYRON H. CLARK.
